CLAIM

(57) The ornamental design for an insect trap, as shown and described.

DESCRIPTION

FIG. 1 is a top, front and right side perspective view of the insect trap showing my new design.

FIG. 2 is a top plan view thereof.

FIG. 3 is a front elevational view thereof.

FIG. 4 is a left side elevational view thereof.

FIG. 5 is a rear elevational view thereof; and,

FIG. 6 is a bottom plain view thereof.

The broken line showing of environment in the drawings is included for the purpose of illustrating only and forms no part of the claimed design.
